CLAIM

The ornamental design for a bag forming animal waste disposal pad, as shown and described.

DESCRIPTION

FIG. 1 is a perspective view of a bag forming animal waste disposal pad in full lines.

FIG. 2 is a front elevational view of the bag forming animal waste disposal pad.

FIG. 3 is a rear elevational view thereof.

FIG. 4 is a top plan view thereof.

FIG. 5 is a bottom plan view thereof.

FIG. 6 is a right side elevational view thereof; and,

FIG. 7 is a left side elevational view thereof.
